ALEXANDER MILLAR, OF ROXBURY, ASSIGNOR TO HIMSELF AND ALFRED ODIORNE, OF MEDFORD, MASSACHUSETTS.

Letters Patent No. 67,896, dated August 20, 1867.

IMPROVED OILER AND FILLER.

The Schedule referred to in these Letters Patent and making part of the same.

TO ALL WHOM IT MAY CONCERN:

Be it known that I, ALEXANDER MILLAR, of Edinburgh, Scotland, residing at Roxbury, in the county of Norfolk, and State of Massachusetts, have invented an Improved Oiler and Filler; and I do hereby declare that the following, taken in connection with the drawings which accompany and form part of this specification, is a description of my invention sufficient to enable those skilled in the art to practise it.

The invention relates to the construction of vessels or cans for oiling machinery, filling lamps, &c.; and consists in constructing the can with a false bottom, in which is a valve, and from which leads a cylinder provided with a piston, the space under the false bottom constituting a shallow charging-chamber, from which leads the ejection pipe, the piston-rod being connected to a wire, so that the piston and oiler may be operated thereby when the oiler is not directly held in and operated by the hand.

The object of my invention is to enable a fixed amount of fluid to be ejected from the can, so as to avoid danger of overflowing the vessel to be filled, and of wasting the oil, and also to enable shafting and other mechanism to be readily oiled without necessity of introducing the hand and arm into proximity with such mechanism.

I am aware of the construction of the oiler patented by John King on the 10th of July, 1866, but such patented oiler has several defects which are obviated in my invention.

The drawing represents a central section of an oiler and filler embodying my invention.

a denotes the can or vessel to contain the lubricant or other fluid; *b* the bottom thereof, at a little distance above which is a parallel false bottom, *c*, the space between constituting a shallow chamber, *d*, from which the fluid is ejected through the discharge pipe *e*, which opens out of one side of the chamber, as seen in the drawing. The false bottom *c* is provided with a valve, *f*, which opens and closes a fluid-passage, *g*, leading from the main reservoir *h* into the charging-chamber *d*. Extending up from the chamber *d*, and opening freely thereinto, is a cylinder, *i*, provided with a piston, *k*, on the end of a piston-rod, *l*, which extends up through the can, and has at its top a thumb-piece, *m*, for operating the piston by hand, while connected thereto is a wire, *n*, extending along a long handle, *o*, made of suitable length to allow the can to be carried by its means to mechanism beyond the reach of the artisan, as will be readily understood. The piston-rod is provided with a spring, *p*, for pressing the piston up to the top of the cylinder, and the piston is preferably made with cup-packing, as seen in the drawing. The mouth *q* of the vessel is covered by a cap, *r*, in the usual manner, but I prefer to place within the mouth a conical strainer, *s*, which shall prevent any foreign matters (which would clog the ejecting tube) from entering the reservoir in charging it with fluid.

The operation of the oiler is as follows: The reservoir being charged with oil through the top *q*, if the piston *k* be now pressed down the expansion of the spring will drive it up when the rod *l* is released, and the fluid will rush through the opening *g* into the chamber *d* to supply the vacuum caused by ascent of piston *k*; the valve *f* falling away from the opening *g* by the pressure of the liquid above. The piston being then forced down, the fluid will be pressed up into the discharge tube *e* and ejected from its point, the valve *f* closing and preventing fluid from being forced back into the reservoir, and causing a fixed quantity to be ejected upon the mechanism to be oiled, or into the vessel to be filled, in accordance with the degree of descent of the piston. Without the false bottom *c* and shallow chamber *d*, and the valve *f*, it would not be practical to effect this, as the fluid would not be ejected from the tube with certainty, but would, much of it, simply flow back into the cylinder if the ejecting tube were connected directly to such cylinder.

I claim, in combination with the reservoir, ejecting pipe, cylinder, and piston, the false bottom *c*, shallow chamber *d*, and valve *f*, constructed and arranged to operate substantially as set forth.

ALEXR. MILLAR.
